DYNAMICALLY BALANCED THERMAL RELAY

Claude M. Hathaway, Niskayuna, N. Y., assignor
to General Electric Company, a corporation of
New York

Application July 9, 1938, Serial No. 218,477

13 Claims. (Cl. 200—139)

My invention relates to thermal relays and more particularly to an improved thermal relay for use in those installations where the relay in operation is subjected to extreme conditions of mechanical vibration. While not limited thereto, my invention is particularly suited for use in controlling the temperature of a piezoelectric device such as may be used with signaling equipment provided in aircraft.

10 Occasions frequently occur where it is desirable that the temperature of an enclosed space be maintained within predetermined temperature limits. The temperature responsive relay is admirably suited to accomplish this result by virtue of the fact that it has a relatively high sensitivity combined with a fairly rugged and rather simple construction. The delicate balance of forces which govern the operation of a relay of this type as it functions to control a source of heat energy 20 has, heretofore, dictated an outstanding limitation to its use in that the relay could not be used under those conditions where, during its operation, it would be subjected to mechanical shock and vibration. Such shock and vibration 25 upsets the delicate balance of forces acting in the relay to create an erroneous operation leading to erratic results. This is particularly objectionable in certain types of service to which the relay would otherwise be adaptable as, for example, in installations of radio apparatus in mobile craft where the limitation here considered leads not only to an impaired temperature control by the relay, but additionally results in a greatly reduced life of the relay through the burning of 30 the electrical contacts with which it is provided and in the creation of an unduly large amount of interference, through the chattering of the relay contacts, with the proper functioning of radio receiving apparatus operating in the immediate 35 neighborhood.

It is an object of my invention to provide a thermally responsive relay whose operation is substantially unaffected by extreme conditions of mechanical shock and vibration.

40 A further object of my invention is to provide a thermal relay wherein magnetic elements are provided to magnetically and electrically damp vibrational movements of the relay elements while aiding the normal temperature responsive movements of the relay elements by effecting a snap-action of the elements to their circuit controlling positions.

The novel features which I believe to be characteristic of my invention are set forth with particularity in the appended claims. My invention

itself, however, both as to its organization and method of operation, together with further objects and advantages thereof, may best be understood by reference to the following description taken in connection with the accompanying drawing in which the single figure represents in elevational view a thermal relay which embodies my invention.

Referring to the single figure of the drawing, each of a pair of bimetallic thermal responsive members 10 is fixedly secured at one end in cantilever fashion to a yieldable member 11 which in turn is supported from a base member 12 of insulating material by a bracket 13. The secured end of the bimetallic member 10 may be 15 positioned in a plurality of selectable positions with respect to the base member 12 by a threaded screw member 14 which screws through a threaded aperture, not shown, in the bracket 13. A lock nut 15 secures the threaded member 14 in 20 adjusted position against the force exerted by the yieldable member 11. The purpose in providing the threaded member 14 will be explained more fully hereinafter.

25 A permanent magnet 16, preferably of a material having relatively high residual magnetism combined with high coercive force, as, the well known material called alnico, is supported in spaced relation to the free ends of the bimetallic members 10 by a bracket 17. The poles 18 of the 30 magnet 16 are adjustably spaced from opposing magnetizable iron members 19, which are secured upon the free ends of the bimetallic members 10, by the provision of securing slots 20 provided in the supporting bracket 17. 35

In addition to the magnetizable members 19, each of the bimetallic members 10 has secured near its free end a hollow cylindrical magnetizable iron sleeve 21 in the center of which, and projecting beyond the end of the sleeve, is a silver 40 contact 22. A sheet of material 23 having good electrical current conductivity, as copper or the like, is secured to the upper surface of each magnetizable member 19 in opposing relation to a corresponding pole 18 of the magnet 16. The 45 purpose in providing the material 23 will be presently explained.

It will be understood that the bimetallic members 10 respond to temperature changes by unequal expansions or contractions of the dissimilar 50 metals which comprise these members with a resultant bending of the member and relative movement of the free end of each. The members 10 are so arranged that increasing values of temperature, or decreasing values as desired, result 55

in movement of the free ends of the bimetallic elements in opposite directions to separate the contacts 22. It will further be understood that a thermal relay as thus constructed may be used to control a source of heat energy by controlling an electrical circuit in which the relay contacts are connected. The controlled electrical circuit is completed through the relay from one of the brackets 13, through a corresponding yieldable member 11 and bimetallic member 10, and through a contact 22 to the corresponding contact and the other bimetallic element 10 and therethrough to the other bracket 13. The upper temperature limit at which the contacts 22 separate is adjusted by adjusting the threaded member 14 in the threaded aperture, not shown, provided in the bracket 13. The threaded member 14 is locked, as previously explained, in adjusted position by the locknut 15. The bimetallic members 10 are substantially duplicates both in the dimensions and materials of their construction and in the method of supporting them from the base 12. Similarly, the elements 10, 21, 22 and 23, which are secured to the free end of each bimetallic member 10, have substantial identity of material, form, and weight. Since, therefore, the bimetallic members 10 are of similar mass and stiffness and are similarly loaded, a relay constructed according to my invention is inherently insensitive to external vibratory forces to which the relay may be subjected. That is, the bimetallic members 10 have at a given instant equal vibrational accelerating forces applied thereto but the members 10 are of equal stiffness and are equally loaded and therefore move together in the same direction under the influence of the vibrational forces. Thus if the relay contacts 22 are in engaging relation at a particular moment during the operation of the relay, mechanical vibration of the relay has no tendency to open the relay contacts. Likewise, if the contacts 22 at a particular time are separated, vibration of the relay does not cause the contacts to reengage. Rapid movement of the free end of the bimetallic member 10, as would be caused by mechanical vibration or shock of the relay, is effectively damped by the eddy currents which are induced in the sheet of current conducting material 23 as this material moves through the magnetic flux which extends between a pole 18 of the magnet 16 and a corresponding magnetizable member 19. The magnitude of the eddy currents thus produced, and therefore the magnitude of the damping action, increases in proportion to increasing values of velocity of the moving material 23. Eddy currents are similarly produced in the magnetizable member 19 as this member is displaced along the face of a respective magnet pole 18 by the movement of the bimetallic member 10. Additionally, the displacement of the magnetizable member 19 with respect to a corresponding magnet pole 18 results in a force which tends to retard or damp the movement of the magnetizable member 19 by virtue of the hysteresis losses in this member through changes in the magnetic density of a unit volume of the material of member 19 with each increment of displacement. All of the retarding or damping forces here considered (i. e., the damping forces produced by the several eddy currents and by the hysteresis losses) exert an influence tending to restrain rapid movements of the bimetallic member 10, and therewith of the magnetizable member 19 and the current conducting material 23.

and thus effectively and quickly damp any movement of the bimetallic member which may result from mechanical vibration of the relay.

It will be evident that the damping forces previously considered are aided by the frictional forces existing between the contacts 22 whenever the contacts are in engaging relation and being thus engaged are displaced relative to one another by movement of the bimetallic members 10 while moving together in the same direction. 10

A thermal relay constructed according to my invention has the additional advantage of a snap-action type of operation. That is, as the contacts 22 separate due to bending of the bimetallic members 10, the air gap between the magnetizable sleeves 21 is increased thereby decreasing the magnetic force of attraction between the sleeves. This decrease in magnetic force occurs at a more rapid rate than the increase of force due to the bending of the bimetallic members 10 under the influence of changing values of temperature with the result that the contacts 22 rapidly move apart to their separated positions as the upper temperature limit is reached. As the temperature drops and the bimetallic members 10 bend toward each other, the magnetic force of attraction between the magnetizable sleeves 21 increases at a more rapid rate than the decrease of the force which maintains the bimetallic members 10 in bent position. Thus as 30 the contacts 22 approach each other, a point is reached at which the contacts move rapidly together into contact. The spacing between the poles 18 of the magnet 16 and the magnetizable members 19 may be adjusted to adjust the degree 35 of snap-action thus provided.

It will now be evident from the above description that my invention provides a temperature responsive relay of the snap-action type which is both dynamically balanced and damped to such a high degree that it may be used under extreme conditions of mechanical vibration even where those conditions are as severe as are commonly encountered in the temperature control of piezo-electric devices provided in radio communication equipment in airplanes. 45

While I have shown a particular embodiment of my invention, it will, of course, be understood that I do not wish to be limited thereto since many different modifications may be made in 50 the arrangement of the elements of the apparatus described. I, of course, contemplate by the appended claims to cover any such modifications as fall within the true spirit and scope of my invention.

What I claim as new and desire to secure by Letters Patent of the United States, is:

1. In a thermal responsive relay, the combination of expansible means movably responsive to temperature variations for controlling an operation, and means for rendering said first-named means substantially unresponsive to mechanical vibrations to which said relay is subjected, said last-named means comprising a current conducting member movable by said expansible means, and means for establishing a magnetic field transverse to the direction of motion of said member, whereby rapid vibrational movements of said expansible means are electrically damped by motion of said member transverse to said field.

2. The combination, in a thermal responsive relay, of means moving in response to changes of temperature to actuate electrical circuit controlling elements, means for mounting said first-named means, said mounting means permitting

vibrational movements of said first-named means under the influence of external vibrational forces to which said relay is subjected, and means for electrically damping said vibrational movements 5 of said first-named means, said last named means comprising a current conducting member movable by said first means, and means for establishing a magnetic field transverse to the direction of motion of said member, whereby rapid 10 vibrational movements of said first means are electrically damped by motion of said member transverse to said field.

3. The combination, in a temperature responsive device, of means movably responsive to temperature variations for controlling an electrical circuit, means for dynamically balancing said first-named means to render the operation of said device roughly insensitive to mechanical vibratory forces to which said device is subjected, 15 and means for magnetically damping vibratory movement of said first-named means to render the operation of said device highly insensitive to said mechanical vibratory forces, said last named means comprising a current conducting member movable by said first means and means for establishing a magnetic field transverse to the direction of motion of said member, whereby rapid vibrational movements of said first means are electrically damped by motion of said member 20 transverse to said field.

4. The combination, in a thermal responsive relay, of expansible means movably responsive to temperature variations for controlling an electrical circuit, said means having a movable portion which vibrates when said relay is subjected 25 to mechanical vibration, means for producing a magnetic field, electric current conducting means in magnetic flux intercepting relation to said last-named means, and means responsive to movement of said first-named means for producing corresponding transverse movement of said current conducting means in said field thereby to produce electrical currents which oppose said vibrational movements of said first-named means 30 to render the operation of said relay substantially unresponsive to mechanical vibration.

5. A thermal responsive relay comprising, in combination, a base member, a pair of bimetallic thermal responsive members each having an end 35 rigidly secured in a plurality of selectable positions on said base member and having a movable end, means responsive to the movement of said movable ends in opposite directions for controlling an electrical circuit, magnetic means, magnetizable means spaced from and in cooperating 40 relation to said magnetic means, and means for effecting relatively rapid movements of said movable ends in opposite directions but relatively slow movements of said movable ends in the same direction, said last-named means including means 45 to increase the length of the magnetic circuit of said magnetic and magnetizable means upon movement of said movable ends away from each other and to produce changes in the magnetization of said magnetizable means by said magnetic means upon movement of said movable ends in the same direction.

6. A thermal responsive relay comprising, in combination, a pair of thermal responsive members, means for supporting said members cantilever fashion in spaced-apart relation with a free 50 end of each opposing and movable in the same direction in response to mechanical vibrations and in opposite directions in response to temperature changes, means responsive to the movement 55

of said free ends in opposite directions for controlling an electrical circuit, a magnet, means for supporting said magnet in spaced relation to said free ends, and means secured to and movable with said free ends through the field of said 5 magnet for accelerating the movement of said free ends in opposite directions while opposing the movement of said free ends in the same direction whereby vibratory movements of said free ends are quickly damped. 10

7. The combination, in a temperature responsive relay, of a pair of bimetallic thermal responsive members, stationary means for supporting said members cantilever fashion in spaced-apart parallel relation, said last-named means positioning said members with their free ends opposing, means responsive to the movement of said free ends in opposite directions for controlling an electrical circuit, a magnet, means for supporting said magnet adjacent said free ends, and magnetizable means secured to each of said free ends and movable therewith adjacent the pole faces of said magnet for damping the concurrent movement of said free ends in the same direction while providing snap-action motion of said free 20 ends when moving in opposite directions. 25

8. In a thermal relay, the combination of a thermal responsive member having a relatively fixed portion and a portion movable under the influence of thermal changes, means responsive 30 to movement of said movable portion for controlling an operation, said relay being subjected during operation to mechanical vibration which tends to produce undesirable movements of said movable portion, and means for reducing said 35 undesirable movement, said last named means including current conducting means arranged to move with said movable portion, and means for establishing a magnetic field transverse to the movement of said current conducting means, 40 whereby current induced in said current conducting means by motion in said field tends to oppose said motion and damps motion of said movable portion.

9. In a thermal relay, the combination of a 45 pair of thermal responsive members each having a relatively fixed portion and a portion movable under the influence of thermal changes, means responsive to movement of said movable portions for controlling an operation, said relay being subjected during operation to mechanical vibration which tends to produce undesirable movements of said movable portions, and means for reducing the effect on said controlled operation of said undesirable movements, said last named means including 50 means for supporting said members in dynamically balanced relation with each other, means for establishing a magnetic field, and means arranged to move individually with each of said movable portions for producing from said magnetic field a force opposing said undesirable 55 movements. 60

10. A dynamically balanced thermal relay comprising, in combination, a pair of thermal responsive devices each having a portion movable in response to changes of temperature, each of the movable portions of said devices having substantially the same period of mechanical vibration, means responsive to the movement of said movable portions with changes of temperature for 70 controlling an operation, means supporting said devices each in dynamically balanced relation with the other to render the operation of said relay roughly unresponsive to mechanical vibration to which said relay is subjected during op- 75

eration, means for producing a magnetic field, and means movable through said magnetic field and responsive to rapid movements of the movable portions of said devices for producing a force opposing said rapid movement whereby the operation of said relay is rendered highly insensitive to vibrational forces.

11. A dynamically balanced thermal relay comprising, in combination, a pair of bimetallic thermal elements each having a portion movable in response to changes of temperature, means for supporting said elements in dynamically balanced relation with said movable portions opposing, means for producing a magnetic field, and means responsive to rapid movement of said movable portions through said magnetic field for producing a force opposing said rapid movement whereby the operation of said relay is rendered unresponsive to external vibrational forces.

12. The combination, in a dynamically balanced thermal relay, of a pair of bimetallic thermal elements, each having the same period of vibration, each of said elements having a portion movable in response to changes of temperature, means for supporting said elements in dynamically balanced relation to each other, means for producing a magnetic field transverse to the direction of movement of said movable portions,

means movable individually with the movable portion of each of said elements for producing with said magnetic field a force opposing rapid vibrational movements of said movable portions, and means movable with at least one of said movable portions for establishing a magnetic path between said movable portions to produce a snap-action operation of said relay.

13. The combination in a thermal responsive device, of a pair of members, each having a fixed portion and a movable portion, said pair of members being so proportioned and placed with respect to each other that shock produces no relative movement between the movable portions of said pair of members, means for producing relative movement between the movable portions of said pair of members upon change in temperature, means responsive to relative movement of said movable portions for controlling an operation, current conducting means associated with 20 and movable by each of said movable portions, and means for establishing a magnetic field through which each of said current conducting means moves, whereby current is induced in said current conducting means upon motion of said 25 movable portions so that said motion is rapidly damped.

CLAUDE M. HATHAWAY.
